Primary Examiner — Melody N Brown*(74) Attorney, Agent, or Firm* — Ralph E. Smith**CLAIM**

The ornamental design for a hood, as shown and described.

DESCRIPTION

FIG. 1 is a front perspective view of a hood showing our new design;
 FIG. 2 is a front view thereof;

FIG. 3 is a rear view thereof;

FIG. 4 is a side view thereof;

FIG. 5 is a top view thereof; and,

FIG. 6 is a bottom view thereof.

It will be understood that the broken lines shown in the drawings illustrate portions of the hood that form no part of the claimed design.
